(57) **CLAIM**

The ornamental design for a catch can, as shown and described.

DESCRIPTION

FIG. 1 is a front perspective exploded view of the catch can.

FIG. 2 is a front view of the catch can.

FIG. 3 is a rear view of the catch can.

FIG. 4 is a left side view of the catch can.

FIG. 5 is a right side view of the catch can.

FIG. 6 is a top view of the catch can.

FIG. 7 is a bottom view of the catch can.

FIG. 8 is an isometric view of the catch can.

FIG. 9 is a front exploded view of the catch can.

FIG. 10 is an isometric exploded view of the catch can.

FIG. 11 is a front cross-sectional view of the catch can.

FIG. 12 is an isometric cross-sectional view of the catch can; and,

FIG. 13 is a front exploded cross-sectional view of the catch can.

The broken lines depict portions of the catch can that form no part of the claimed design.
